UNITED STATES PATENT OFFICE

114,740

DESIGN FOR A TEXTILE FABRIC OR SIMILAR ARTICLE

Carina Dondo, New York, N. Y.

Application February 28, 1939, Serial No. 83,253

Term of patent 3½ years

To all whom it may concern:

Be it known that I, Carina Dondo, a citizen of the United States of America, residing in the city of New York, county of New York, and State of New York, have invented a new, original, and ornamental Design for a Textile Fabric or Similar Article, of which the following is a specification, reference being had to the accompanying drawing, forming part thereof.

The figure on the drawing is a plan view of a textile fabric or similar article showing my new design.

I claim:

The ornamental design for a textile fabric or similar article, substantially as shown.

CARINA DONDO.
